ATTYS.

UNITED STATES PATENT OFFICE.

GEORGE F. HOGAN, OF CHICAGO, ILLINOIS.

CLOSURE FOR ENVELOPS.

1,105,785.

Specification of Letters Patent.

Patented Aug. 4, 1914.

Application filed April 18, 1913. Serial No. 761,933.

To all whom it may concern:

Be it known that I, GEORGE F. HOGAN, a citizen of the United States, and a resident of Chicago, in the county of Cook and State 5 of Illinois, have invented certain new and useful Improvements in Closures for Envelops, of which the following is a specification.

The main objects of this invention are to 10 provide a closure for envelops in which there will be a minimum waste of material; also to provide a closure which will prevent merchandise which is being sent in the envelop from working against the flap of the 15 envelop; and further to provide a closure in which the merchandise is so remote from the opening that the possibility of any of the contents spilling, is practically removed. It 20 is the practice in sending merchandise by mail, not to seal the envelop but to secure the flap by a fastener. With the ordinary single flap envelop, when closed by a fastener, the entire width of the envelop is sufficiently exposed to permit the contents 25 of the envelop to creep out.

It is the object of the present invention to provide a closure for envelops, especially for use with merchandise where the envelops are closed by a fastener, wherein the 30 greatest possible portion of the opening is securely closed, and to position the necessary exposed portion of the opening so remote from the main portion of the interior 35 of the envelop that the possibility of material creeping out, is practically removed.

It is still another object of the invention to provide an envelop with a secure closure, the envelop proper and closure being all in one piece.

These and other features, capabilities and 40 advantages of the invention will become apparent from a detailed description of the accompanying drawings illustrating a specific embodiment of the invention in which—

Figure 1 is an elevation of the closed envelop provided with the improved closure. Fig. 2 is a perspective view showing the closure before being closed with the body of the envelop broken away. Fig. 3 is an elevation 45 of the closure blank showing the scorings on which the folds are made when closing the closure. Fig. 4 is an elevation of the closure partially folded with the body of the envelop and a corner of the closure broken away, and Fig. 5 is a perspective, similar to 50 Fig. 4 with a portion of the closure folded

down to show the respective positions of the creases when the closure is folded.

In the construction shown, the envelop has the opening provided at its narrow end, and when closed ready for mailing, the closure 60 has two inclined sides and a straight upper end as shown in Fig. 1. The outline of the closure portion of the blank from which the envelop is made, is rectangular with a 65 recess cut out of each corner as shown in Fig. 3, the side 10 of each of the recesses being perpendicular to the upper edge 11 of the blank and the lower side 12 of each of the recesses being parallel with such upper 70 edge of the blank.

In the manufacture of the envelop, the article is passed through a scoring machine to produce the requisite scores. In addition to the two scores 13, 13 for the sides of the 75 envelop which run perpendicular to the upper edge 11 of the blank, the closure end of the envelop is provided with scores to form the closure. Parallel with the upper edge 11 of the blank, there is a score 14 running completely across the blank. This score 14 is approximately at twice the distance from the upper edge 11 of the blank that the lower side 12 of the recess is. At the right of the closure portion a score 15 80 runs from the point where the score 13 crosses the score 14 to the angle 16 of the corner recess. To facilitate the description, the point where the score 13 meets the edge 11 is designated 18. A point 17 on edge 11 85 designates a distance to the left from point 18 which is approximately the distance from the upper edge 11 to the score 14. From this point 17, a score 19 is extended diagonally to the point where the score 13 crosses the 90 score 14. At a point 20 on the upper edge 11 which point 20 is at a distance from the side 10 to the left thereof of approximately the length of the side 12, a score 21 is extended down to meet score 19. The left of 100 the closure end of the blank is identical with the right only that the lines run in the opposite direction. Therefore, the scores of the left side of the closure blank may be designated the same as those of the right side. 105 Then, from the point where the score 21 meets the score 19 of the right side, a score 22 is extended to the left running parallel with the upper edge 11 to meet the score 19 of the left side which is at a point where 110 score 21 of the left side meets score 19 of the left side.

When the envelop is prepared for the dealer, the side 23 of the blank may be folded over onto the side 24 and pasted in the usual manner, and the flap 25, see Fig. 5 1, folded up and pasted over the same, and the upper portion or closure portion of the envelop is left in the condition illustrated in Fig. 2, in which condition the envelops are sold to the trade. When the consumer 10 uses the envelop to mail or forward merchandise, he will, after filling the envelop, thrust the corners 18, 18 inward to the position shown in Fig. 4. Then, with reference to Fig. 4, he will fold the edge 11 over so that the eyelet 26 can be engaged by the fingers 27, 27 which are secured in the upper end of the side 23 of the blank. These 15 fingers 27, 27 after being passed through the eyelet 26 are pressed down, in the present instance, in opposite directions, in a line parallel to the upper edge 11. The space where the eyelet is positioned, is made as narrow as possible by having the edge 11 on either side of it bend down as close as possible to the eyelet without interfering with its utility. Furthermore, the space is made 20 so narrow that when the fingers 27, 27 are secured in place, they project over the location of the edges 11, 11 as shown in Fig. 1, and thus the edges 11, 11 will serve as a 25 reinforcement, should the ends of the fingers 27, 27 bore through the first layer of paper. To further lock the envelop, the entire closure end may be bent over on the score 14. 30 When the entire closure end of the envelop is bent over on the score 14 with the fastener lying against the body of the envelop, an additional protection to the fastener will 35 thereby be afforded.

40 It will be seen with reference to Fig. 4, that merchandise which is inclosed in the envelop will be prevented from working itself up against the flap of the envelop on account of the projections formed by the inward 45 turned corners 18, 18. It will also be seen that a very small portion of the opening can be reached by loose merchandise such as grain, and that this small portion of the

opening is so remote from the bulk of the merchandise, that the possibility of any material creeping out through it, is practically removed.

While there is herein shown and described but one embodiment of the invention, it is to be understood that various changes and 55 modifications may be made by those skilled in the art without departing from the scope of the invention in the appended claims.

Having thus described my invention, what I claim as new and desire to secure by Letters Patent is:

1. In a flat merchandise envelop having a longitudinal seam and a closed bottom, a closure for the top comprising corners doubled inward between the front and rear 65 walls of the envelop and lying flat against those walls; the upper end of the envelop being bent over the doubled-in corners and fastened in place.

2. A flat merchandise envelop having its 70 corners at the open end thereof doubled inward between the front and rear walls of the envelop and lying flat against those walls, and with the front wall projecting beyond the rear wall, and adapted to bend 75 back to overlap the rear wall and there fasten in place to keep the folded-in portions from coming out again.

3. A merchandise envelop having a longitudinal seam and having a closure comprising a notched rear wall and a front wall projecting beyond the notch, said closure having corners doubled in on either side of this notch to form a flap of that portion of the front wall which projects beyond the 85 notch, said flap being adapted to fold down over the rear wall and there fasten in place to keep the folded-in portions from coming out.

In witness whereof, I hereunto subscribe 90 my name to this specification in the presence of two witnesses.

GEORGE F. HOGAN.
